US00D898908S

(12) **United States Design Patent** (10) Patent No.: **US D898,908 S**
Denzer et al. (45) Date of Patent: **** Oct. 13, 2020**

(54) **PHARMACEUTICAL PRODUCT CASSETTE
FOR AN INJECTION DEVICE**

A61M 5/31; A61M 5/3146; A61M 5/3129; A61M 5/3148; A61M 5/315

See application file for complete search history.

CLAIM

The ornamental design for a pharmaceutical product cassette for an injection device, as shown and described.

DESCRIPTION

FIG. 1 is a top perspective view of a fourth embodiment of a pharmaceutical product cassette for an injection device showing the new design;

FIG. 2 is a bottom perspective view thereof;

FIG. 3 is a bottom elevation view thereof;

FIG. 4 is a top elevation view thereof;

FIG. 5 is a side elevation view thereof;

FIG. 6 is a front view thereof; and,

FIG. 7 is a rear view thereof.

The broken lines represent the portions of the design that form no part of the claim.

1 Claim, 6 Drawing Sheets

FIG. 1

FIG. 2

FIG. 3

FIG. 4

FIG. 5

FIG. 6

FIG. 7
